Attorney.

UNITED STATES PATENT OFFICE.

FLOYD G. WITHROW, OF GRAND RAPIDS, MICHIGAN.

CARBURETOR-CHOKE-VALVE SPRING.

Application filed August 10, 1925. Serial No. 49,496.

This invention relates to carburetor choke valve springs and its object is to provide an extremely simple spring which may be quickly and easily attached to a carburetor 5 to yieldably retain the so-called choke valve thereof in open position. Although this spring is intended as a replacement part to be applied to the carburetor after the spring usually provided for the choke valve has 10 broken, which is a very frequent occurrence, it is not limited to this use but may readily be used in the first instance as an original part of the carburetor.

The invention provides various novel 15 features of construction and arrangement which will hereinafter be more fully described and particularly pointed out in the claim, reference being had to the accompanying drawing, in which,

20 Fig. 1 is an elevation of a carburetor having a choke valve spring embodying this invention applied in operative position thereto.

25 Fig. 2 is a fragmentary section showing the choke valve in its normal position.

Fig. 3 is a perspective view of the spring removed from the carburetor, and

30 Fig. 4 is a fragmentary view illustrating the construction at one end of the said spring.

Like numbers refer to like parts in the different figures of the drawing.

The carburetor for which this choke valve spring is especially adapted is of the type 35 commonly used in Ford automobiles and it comprises a body portion 1 having an air inlet 2 and a gas outlet 3 disposed diametrically opposite. A float chamber 4 is located beneath the body and a gasoline inlet 5 enters one side of the body near its center.

40 At the air inlet 2 the customary choke valve 6 of the butterfly type is provided which is mounted upon a shaft 6^a and the bell crank lever 7 fixed to the shaft 6^a is provided for manipulating the choke valve. The lever 7 has a hub 8 projecting from its outer surface and surrounding the shaft 6^a and it also has stop lugs 9 and 10 which engage the pin 11 on the carburetor body to limit the movement of the lever and consequently the valve in either direction. A pull rod 12 is connected to one arm of the bell crank lever 7 and extends upwardly and 45 may be manually operated to close the choke valve.

50 At the outlet 3 of the carburetor a flange

13 is provided on the body which engages a similarly shaped flange 14 on the intake manifold 15 and cap screws 16 extend through the flange 13 and are threaded into the flange 14 to connect the carburetor to the manifold.

During normal operation of the engine the choke valve should remain in wide open position, in which position the lug 9 on the bell crank lever engages the stop pin 11 and it is the object of the spring embodying this invention to yieldably retain the choke valve in this open position. When it is desired to enrich the mixture of the gasoline and air fed to the engine, which is customarily done for a short period in starting the engine and also for short periods under some other conditions, the pull rod 12 is manually operated to rotate the shaft 6^a and either wholly or partially close the choke valve 6 but when the pull rod 12 is released it is desirable to have the choke valve automatically return to wide open position.

The spring which I have invented comprises a single piece of wire formed into a spring coil 17 substantially midway between the ends of the wire from which two end portions 18 and 19 extend downwardly and away from each other. The portion 19 terminates in a hook 20, while the portion 18 is bent into an eye 21, thence extended for a short distance and turned at right angles making a short section 22 which is again turned at right angles to make the terminal section 23.

55 In applying this spring to the carburetor the hook 20 is hooked over the pin 11 and the parts 18 and 19 sprung toward each other, the bent end including sections 22 and 23 passing through an opening in the end of the arm 7^a of the bell crank lever. To the eye 21 a wire 24 may be connected and extend forwardly to and through the radiator of the automobile so that the choke may be operated while the engine is being cranked.

60 It will be seen that this device is an extremely simple part made from a single piece of spring wire and so shaped that it may be installed by simply fitting it into place, this being a practically instantaneous operation. When in operative position the spring exerts a constant downward pressure 65 against the arm 7^a of the bell crank lever 7 with which it is hooked and yieldably holds the lug 9 against the stop 11. When the bell

crank lever is moved to close the valve the spring will flex and will return the valve to its normal open position when released.

I claim:

5 A choke valve spring formed from a single piece of wire comprising a central coil and end portions extending therefrom, a hook formed at one end of one of said end

portions, an eye formed adjacent the end of the opposite end portion the wire being then 10 bent laterally for a distance at right angles and then again at right angles in the same direction as said end portions, substantially as described.

In testimony whereof I affix my signature.

FLOYD G. WITHROW.
